UNITED STATES PATENT OFFICE

2,509,132

HOLDER FOR PAPER CUPS

Herman Carew, Easton, Pa., assignor to Dixie Cup Company, Chicago, Ill., a corporation of Delaware

Application November 15, 1943, Serial No. 510,311

10 Claims. (Cl. 65—61)

1

This invention relates to improvements in a holder for paper cups as well as to the combination of a paper cup and holder, such as is highly desirable for use in drug, confectionary, and stores of similar character wherein individual soft drinks, sodas, and the like are dispensed, although the invention may have other uses and purposes as will be apparent to one skilled in the art.

The instant application is a continuation-in-part of my co-pending application entitled "Paper cup and holder therefor," filed March 8, 1941, Serial No. 382,300, now abandoned, and the broader or generic claims covering this invention are contained in that co-pending application.

It has long been desirable to use paper drinking cups or vessels in a holder at soda fountains and similar locations where individual soft drinks and the like are dispensed. The use of such apparatus results in a material saving of labor in that the paper cup is destroyed after each usage and if the holders and cups are of proper relative sizes, the cups project sufficiently far out of the holder as to avoid any contact of the lips of the user with the holder, so that the holder need be washed only very infrequently.

In the past, extreme difficulty has been experienced in maintaining the cup within the holder until it has been used by a customer. When the holder was tipped sufficiently during drinking to enable the customer to drain the contents of the cup, there was extreme danger of some of the contents as well as the cup becoming free of the holder and cascading down over the wearing apparel of the user. Prior to my aforesaid co-pending application either the cup rested loosely in the holder or some mechanical means were utilized to maintain the cup in the holder, but these means required either a definite and tedious positioning of the cup relatively to the holder, or some manipulation of the holder by the operator. In the event the holder automatically engaged the rim of the cup, no manipulation was necessary, but such means were extremely objectionable in that there was danger of the user's lips or the contents of the cup contacting that portion of the holder, and so the holder had to be washed after each usage and there was no saving in labor over the use of the customary glass. In the case of conical paper cups of a size to hold an ice cream soda or some similar confection, the danger of the cup falling out of the holder onto the apparel of the user was aggravated by virtue of the top-heavy character of the cup. A highly

2

satisfactory solution to this problem has been presented and claimed in my aforesaid co-pending application, the instant application is directed to another specific solution of the same problem.

It is therefore an object of this invention to provide a holder for a paper cup, especially a conical paper cup, designed to receive the paper cup apex first and establish a firm engagement with the cup sufficient to prevent accidental dislodgment of the cup, regardless of the nature or structure of the paper cup, the engagement resulting by a relative substantially axial movement between the cup and the holder.

15 Another object of the invention resides in the provision of a holder for a paper cup which holder includes a formation defining a cup receiving cavity, with means projecting into that cavity from the wall thereof to establish an engagement with the received cup.

20 It is also an object of this invention to provide a holder for a paper cup, especially a conical paper cup, which holder embodies a formation defining a cup receiving cavity, and includes means projecting into that cavity from the wall thereof to provide a biting engagement with the wall of the cup.

25 Another object of this invention to provide a holder for a paper cup, especially a conical paper cup, which holder includes a formation defining a cup receiving cavity with a plurality of projections extending into the cavity from the wall thereof, the projections being spaced apart sufficiently so that each projection provides its own individual and separate gripping indentation in the wall of the received cup.

30 Another feature of the invention resides in the provision of a holder for a paper cup which includes a formation defining a cup receiving cavity with means projecting into the cavity from the wall thereof in the nature of individual separated projections, each of which has an inner surface disposed obliquely so that said surface slopes both downwardly and inwardly.

35 Still a further feature of the invention resides in the provision of a holder for a paper cup, especially a conical paper cup, which holder embodies a formation defining a cup receiving cavity, and projections extending into said cavity from the wall thereof, each projection being obliquely shaped at its inner end, with the under surface of the projection extending substantially horizontally so as to provide both a somewhat biting effect and a shoulder effect for holding the cup within the holder.

40 Another object of the invention resides in the

provision of a holder for a paper cup, especially a convolutely wound paper cup, with separated projections extending into the cup receiving portion of the holder from the wall thereof, said projections being sufficiently numerous so that at least one will engage over the exposed edge of one of the convolutions of the cup in a latching manner and thus retain the cup in the holder against accidental dislodgment, such engagement being effected regardless of the relative circumferential position of the cup and holder at the time they are joined.

Still a further object of the invention resides in the provision of a holder for a paper cup, especially a conical paper cup, which holder embodies a formation defining an open bottomed tubular cup receiving portion, the apical portion of the conical cup extending through the opening in the bottom of said portion, and the holder being provided with an annular series of separated and spaced projections extending from the wall of said portion directly into the cup receiving cavity near the bottom thereof to establish a tight frictional engagement with the cup wall sufficient to prevent accidental dislodgment of the cup.

Still a further object of this invention resides in the provision of a novel combination of a conical paper cup and a holder therefor, the holder being arranged to effect a positive engagement with the cup, and regardless of the construction of the cup, upon an axial movement between the cup and the holder without the need of any circumferential registry between the articles.

While some of the more salient features, characteristics and advantages of the present invention have been pointed out, others will be apparent from the following disclosures, taken in conjunction with the accompanying drawings, in which:

Figure 1 is a top plan view of a cup holder embodying the principles of this invention;

Figure 2 is a central vertical sectional view through the holder of Figure 1, illustrating a conical paper cup in the holder in elevation, and showing parts of the holder in elevation, for purposes of clarity;

Figure 3 is a transverse plan sectional view through the holder itself taken substantially as indicated by the line III—III of Figure 2;

Figure 4 is a fragmentary enlargement of the lower right-hand central portion of Figure 2;

Figure 5 is a side elevational view of the cup seen in Figure 2 turned to the left approximately ninety degrees from the position seen in Figure 2, illustrating diagrammatically the effect on the cup of its engagement in the holder;

Figure 6 is a view similar in character to Figure 2, illustrating a holder in section taken substantially as indicated by the line VI—VI of Figure 3, and illustrating a cup of somewhat different construction than the cup of Figure 2 in position in the holder, the effect of the engagement with the holder on the cup being indicated diagrammatically; and

Figure 7 is a fragmentary enlargement similar in character to Figure 4 illustrating the engagement between the holder and cup of Figure 6.

As shown on the drawings:

In connection with paper cups and holders for the individual dispensing of soft drinks and the like, it is desirable that the attendant at the soda fountain never need contact a paper cup with his hands prior to the use of the cup by the customer, and it is further desirable that the attend-

ant need do nothing whatever but place the holder over a cup to establish the holding engagement between the cup and holder sufficient to prevent accidental dislodgement of the cup. It is a waste of time for the attendant to establish a certain degree of circumferential registry between a cup and holder before a proper holding engagement can be established, and likewise it is a waste of time for the attendant to manipulate some mechanical part of the holder to establish such engagement. Not only is it a waste of time, but it is highly conducive to carelessness in handling, and results frequently in a cup that is not held within the holder, and more frequently results in the attendant taking the paper cup in his naked hands and placing it in the holder in proper position. As stated above, the desirable way is for the attendant merely to grasp the holder, place it over a cup with an axial movement, and the latching engagement is established. Most frequently, especially with conical cups, the cups are kept in a suitable holder in inverted position, apexes up, and the cups are stacked in nested relationship so as to conserve space. The attendant then merely grasps the holder near the bottom, inverts it, places it over the uppermost inverted cup on the stack, and without at all touching the cup picks the cup up with the holder, the latching engagement having been established upon the application of the holder with a slight pressure. This latter course is the manner in which the instant invention operates.

In the drawings, I have illustrated the same holder associated with two conical cups of different construction, to bring out more forcibly the fact that the holder operates satisfactorily without regard to the particular construction of the cup, although a more positive engagement might be established with a cup of the character seen in Figures 2 and 5, than with the cup seen in Figure 6.

With reference now to Figures 1 to 4, inclusive, it will be seen that the holder selected for illustration, indicated by numeral 1 may be generally of hour-glass shape and formed of any suitable material, such as a plastic. The holder, if so desired, may be provided with a suitable handle 2 although the handle is not necessary, it being easy to grasp the holder in the waist portion and elevate the cup to the mouth. The holder itself is preferably tubular, that is having an opening completely therethrough, to facilitate cleansing when cleansing is necessary. The upper portion of the holder is formed to define a cup receiving cavity 3 having a bottom opening 4, seen in Figure 1. This cavity is partially defined by a tubular extension 5 spaced from the outer end lower portion 6 of the holder which is flared to form a suitable base.

In connection with conical paper cups, it has been found desirable to effect the engagement between the cup and the holder with the apical region of the cup thereby adding to the stability of the cup and holder both when the cup is empty and when it is filled with some commodity. To this end, near the bottom of the cavity 3 an annular series of pins 7 has been embedded in the wall of the holder, in the illustrated instance, each pin extending within both the tubular extension 5 and the outer wall portion 6. These pins may also be of any suitable material, and in the illustrated instance, the pins are shown as metal and as inserted in a smooth bore drilled in the holder wall.

It will be noted that the inner end of each pin

is cut off obliquely as indicated at 8 so that such inner end slopes both downwardly and inwardly toward the axis of the holder. Each pin projects beyond the inner wall defining the cavity 3 and extends into the cavity, as clearly seen in Figure 2. The under side of each pin extends substantially horizontally and the cutting of the inner edge ends abruptly so that there is a shoulder formation as indicated at 9 in Figure 2 on each pin. It will also be noted that the lower edge portion of the pin adjacent the shoulder is relatively sharp so as to resist an outward movement of the cup after engagement has once been established.

The pins 7 are fixed in position so as to form substantially an integral portion of the holder wall. Further, the pins are preferably spaced sufficiently apart, and so sized, to form projections within the cavity each capable of making individual and separate indentations in the wall of a cup. The projections or pins may be of any desired number, and are preferably equally spaced apart. In the illustrated instance, there are six projections or pins shown, and this number is highly satisfactory for practically every cup.

With reference to Figures 2 and 5, it will be seen that the cup 10 shown associated with the holder is a convolutely wound conical paper cup made from a single blank of material. The single blank may be of substantially a sector shape, and may be wound from one side edge to the other, the large arc of the blank defining the mouth edge of the finished cup. Thus, overlapping portions of the blank are provided, and these portions are preferably held together by a suitable adhesive. The edge of the outer overlapping portion of the blank defines a substantially convolute line around the container as indicated at 11 and it will be noted that a portion of this edge as indicated at 12 in Figure 5 approaches the horizontal in its travel for at least a partial revolution about the cup. Such edge portion 11-12 will be slightly free from the inner part of the cup, because the glue holding the overlapping portions together should not be brought completely to the edge of the outer overlapping portion to avoid any danger of glue being squeezed onto the exposed surface of the cup during the forming operation and thus adhere to the next adjacent cup in a stack of nested cups. Consequently, the glue is kept back from the very edge and so the edge portion 11-12 is free from the inner wall of the cup.

When the holder is placed axially over a paper cup, either the uppermost cup of an inverted stack of nested cups, or the lowermost cup in an upright stack of nested cups contained in a dispenser, upon a slight pressure the projections or pins 7 will frictionally engage the cup wall. Preferably these projections are sufficient in number, and six is a satisfactory number for this purpose, so that at least one of the pins or projections will engage over the edge portion 12 of the cup as indicated at 13 in Figures 2 and 5 and as seen very clearly in Figure 4 so that a latching engagement is provided between that particular projection or pin and the paper cup. As the cup is pushed into the holder or the holder pressed over the cup, the edge portion 12 will flex in passing the projection, and then expand into engagement beneath the horizontal under edge of the projection. It is not necessary that at the point of such latching engagement the edge portion of the cup be traveling very closely

to the horizontal, but only sufficiently closely to the horizontal to permit a holding engagement, as illustrated at 13 in Figure 2. Thus, the cup may be held in the holder against accidental dislodgment by the one or two projections latching engaged over the edge of the outer convolution of the cup. However, the other projections do not result in wasted effort, these projections also frictionally engaging the wall of the cup in a manner tending to resist outward movement of the cup. After use, when the cup is withdrawn from the holder against the action of the holding elements for disposal, the effect of the pins may be noted on the outside wall of the cup as indicated at 14 in Figure 5. It will be noted that each of the pins has distorted the cup wall somewhat, while the pin engaged in a latching manner over the edge of the outer convolution has caused a distortion of the paper adjacent this point. Such is what usually happens with a holder of this type, although it is understood that the showing in Figure 5 of the effect of the pins on the cup wall is diagrammatic and that the actual effect will not be identical with this disclosure at all times. However, the knife edge on the projections or pins mainly caused by the horizontally extending under surface of the pins is usually sufficient to cause a surface distortion of the container when the latter is removed from the holder.

It will be noted that preferably there should be a proportioning of sizes between the holder and the cup. That is, there would be a different size of holder for a cup approximately six ounces and for a cup approximately twelve ounces. If there is to be a latching engagement with one or more of the pins and the edge portion of the cup, the cup should extend through the tubular part 5 or through the opening at the bottom of the receiving cavity a sufficient extent to provide such engagement. Likewise, the mouth end of the cup should project sufficiently out of the holder so as to eliminate the probability of contact of the user's lips with the holder so that the holder need not be washed only very infrequently. The proportioning of sizes between cups and holders need not be carried out to any considerable extent, however, two or three sizes of holders being usually sufficient for complete soda fountain service.

50 In Figures 6 and 7 I have illustrated the use of the holder with a cup 15 of different construction than the cup 10 above described. In this instance, the cup is conical, made of a single blank of material, but is not convolutely wound. The blank may be somewhat of a sector shape, and the approximately radial edges are brought together with the margins thereadjacent in overlapping relationship to form a straight side seam 16 the parts of which may be held together with a suitable adhesive. With the use of the cup 15 there will not be any latching engagement as above described over the edge of a convolution, but the projections or pins 7 will each cause an indentation in the wall of the cup substantially as indicated at 17 in the exaggerated showing seen in Figure 7. It will be noted that the pins or projections each causes its own individual and separate indentation in the wall of the cup and the effect is of a biting engagement with the cup wall, as was the case with the previously described showing and illustrated in an exaggerated manner in Figure 4. Such biting engagement is sufficient to hold the cup in the holder against accidental dislodgment, and when 75 the cup is removed from the holder for disposal,

there will be at least in most cases, a surface distortion of the cup wall as indicated at 14 in Figure 6, in the same manner as previously discussed, this showing also being diagrammatic. In the event one of the pins or projections should contact the exposed edge of the seam 16, it will provide an added holding of the cup by virtue of a distortion of this edge as indicated at 18 in Figure 6. However, this will happen only comparatively rarely, and is not necessary for the adequate holding of the cup.

In operation, with substantially any form of conical paper cup, it is a simple expedient to merely push the holder axially over the cup, exert a slight degree of pressure, and there is a sufficiently firm engagement between the cup and holder. In the event the cup is of the convolute type, one or more projections of the holder will establish a latching engagement with a part of the outermost convolution. In the event the cup does not have any convolutions, the biting engagement present at all times is amply sufficient to hold the cup against accidental dislodgment during use.

It will further be appreciated that the cups themselves are highly economical, and the holder is of economical and extremely durable construction, and may be repeatedly used for a considerable time. Labor is saved by virtue of the fact that each cup is destroyed after one usage, and the holder, not becoming dirtied or contaminated for a length of time, can be repeatedly used without washing. Fountain service is materially expedited with the aid of the present invention due to the speed with which a holder may be placed over the terminal cup of the stack, and the cup withdrawn from the stack locked in the holder.

It will, of course, be understood that various details of construction may be varied through a wide range without departing from the principles of this invention and it is, therefore, not the purpose to limit the patent granted hereon otherwise than necessitated by the scope of the appended claims.

I claim as follows:

1. As an article of manufacture, a conical paper cup holder having an open bottom cavity therein for the reception of a conical paper cup apex first, and an annular series of spaced projections extending into said cavity in position to engage the wall of a conical paper cup, said projections each slanting off downwardly and inwardly to provide a relatively sharp lower edge capable of biting into the wall of a cup extending through the open bottom of said cavity.

2. A holder for a conical paper cup, including a tubular portion shaped to receive therein a conical paper cup apex first and having an opening in the bottom through which the apical region of the cup extends, and a plurality of spaced cup holding projections extending laterally inwardly beyond the inner wall of said tubular portion, said projections each having an oblique inside face extending inwardly and downwardly so the lower edge is farther from the wall of said tubular portion than the upper edge.

3. A holder for a conical paper cup, said holder including a tubular portion to receive the cup therein apex first, and a plurality of spaced metallic pins embedded in the wall of said tubular portion, said pins being arranged in an annular series and having their inner ends cut obliquely to provide a relatively sharp lower edge

projecting inwardly farther than the upper edges thereof.

4. A cup holding receptacle, which comprises in combination a body portion and a base, a constricted wall area between said body portion and said base supporting a bottom end portion of a cup, and an annular series of spaced projections disposed oppositely of each other within said constricted area and frictionally engaging and indenting the side wall portion of the cup bottom end to secure the same in fixed position prior to and after said cup is up-ended during use in emptying its contents.

5. In a holder for an initially completely empty conically shaped flexible-wall cup, a receptacle body portion of generally complementary inside shape to that of the cup and having a supporting base portion joined thereto by a constricted wall area supporting the bottom end portion of the cup spaced from the cup apex and defining an opening through which the apex extends freely, and annularly spaced inwardly projecting means at said constricted wall area for frictionally engaging the outer surface of the empty cup bottom portion to secure the same in fixed position in response to simple axial assembly movement of the holder to lodge said cup bottom portion against said constricted wall area.

6. A holder for a paper cup, including a body part having a wall forming an open bottomed cavity for the reception of a conical paper cup apex first, and metallic means supported by the wall of said body adjacent the lower end of said cavity comprising an annular series of elements projecting inwardly beyond the wall of the cavity for automatic frictional engagement with the wall of the cup to lock the cup in the holder against accidental dislodgement when the holder is pressed axially over the terminal cup of a stack.

7. A holder for a paper cup, including a body part having a wall forming an open bottomed cavity for the reception of a conical paper cup apex first, and metallic means supported by the wall of said body adjacent the lower end of said cavity comprising an annular series of elements projecting inwardly beyond the wall of the cavity for automatic frictional engagement with the wall of the cup when the holder is pressed axially over the terminal cup of a stack to lock the cup in the holder against accidental dislodgement, said elements having relatively sharp edges on their inner portions to in effect bitingly engage the external cup wall.

8. A holder arranged to receive therein a convolutely wound conical paper cup having overlapping portions one of which provides an exposed edge on the outside of the cup, said holder including a body portion having a wall defining a cavity therein to receive the conical cup apex first with the apex projecting below the cavity, and a series of annularly spaced projections extending into said cavity from the wall thereof adjacent the bottom thereof, said projections being sufficient in number so at least one will engage over the exposed edge on the cup upon axial relative movement between the cup and holder.

9. A holder for a paper cup, including a body portion having a tubular cup engaging wall defining a cavity for the reception of a completely empty paper cup bottom first, and a plurality of projections extending radially inwardly from points near the bottom of said cup engaging wall, each projection having an edge portion for automatic frictional engagement with the wall

of the empty cup upon a mere relative axial movement between the cup and holder, and said projections extending inwardly a sufficient distance to distort the empty cup wall and insure a positive holding of the cup against accidental dislodgement while in use in the holder.

10. A holder for a paper cup, including a body portion having a tubular cup engaging wall defining an open-bottomed cavity for the reception of a completely empty paper cup bottom first, with the cup bottom projecting below the cup engaging wall, and a plurality of projections extending radially inwardly from points near the bottom of said cup engaging wall, each projection having a relatively sharp edge for automatic biting engagement with the outer wall of the empty cup upon a simple relative axial movement between the cup and holder to maintain the cup in the holder against accidental dislodgement.
